UNITED STATES PATENT OFFICE.

WILLIAM W. DICKINSON, JR., OF LITTLE ROCK, ARKANSAS.

METHOD AND MEANS FOR SETTING BRICK MECHANICALLY IN SPACED REGULAR RELATION, AS IN KILNS AND THE LIKE.

1,334,892.

Specification of Letters Patent. Patented Mar. 23, 1920.

Original application filed March 25, 1918, Serial No. 224,461. Divided and this application filed January 6, 1919. Serial No. 269,782.

To all whom it may concern:

Be it known that I, WILLIAM WALLACE DICKINSON, Jr., a citizen of the United States, residing at Little Rock, in the county 5 of Pulaski and State of Arkansas, have invented a certain new and useful Improvement in Methods and Means for Setting Brick Mechanically in Spaced Regular Relation, as in Kilns and the like, of which the 10 following is a full, clear, and exact description, reference being had to the accompanying drawings.

This invention relates to the manufacture of bricks and has for its general object to 15 improve the methods and appliances for handling the bricks between the time of their delivery by the brick machine to the time when they are set upon the conveyance whereby they are transported to the user, 20 this application being a division of my prior application No. 224,461 filed March 25, 1918.

More particularly the object of this invention concerns the provision of a device 25 whereby unburned brick can be set in pre-determined spaced relation upon a kiln for the purpose of drying or burning the same, or whereby burned brick can be transported from place to place and deposited in pre-determined piled relation without manual handling. In my accompanying application filed 30 March 20, 1918, Serial No. 223,555, I have illustrated certain brick conveying pallets together with means for transporting those 35 pallets from point to point and for loading the same with bricks arranged in ordered ranks; the present application concerns more particularly the method and means of discharging said bricks from said pallets so 40 as to produce a kiln or other ordered pile without breaking or crushing the bricks themselves and without the necessity of manual handling; while the construction of the pallet itself and the carrier thereof constitutes the subject matter of a third application, filed March 27, 1918, Serial No. 45 225,077.

In the drawings accompanying and forming a part of this application I have shown 50 one of the many operative forms in which my invention may be embodied and performed; although it will be understood that these drawings are merely illustrative and not limiting of my invention. In these

drawings Figure 1 is a diagrammatic view 55 of my improved system; Fig. 2 is a detail view showing the method of removing the pallets from and restoring them to the transporting device; Fig. 3 is a sectional view on the line 3—3 of Fig. 2; Fig. 4 illustrates the method of discharging the bricks 60 from the pallet and of setting the same in spaced relation as in building a kiln; Fig. 5 illustrates the method of forming the kiln-arches; Fig. 6 is a perspective view of a portion 65 of the pallet carrier; Fig. 7 is a top plan view of the carrier and the pallet thereon at the instant of discharging the bricks therefrom; and Fig. 8 illustrates in side elevation a rail-car having a pallet thereon. 70

Describing the drawings with regard to the reference characters thereon, A represents a conveying belt or chute, B a dry house, and C a kiln shed or kiln yard. D represents a transporting system of any convenient or suitable type, such as cars running upon a track or an endless moving belt or cable. In the present embodiment I have shown the same as passing by the conveyer A so that the pallet thereon may receive the 80 bricks delivered thereby either in the mode illustrated in my copending application, Serial No. 223,555 or in any other suitable manner; I have next shown the transporting device as passing through the dry house, 85 so that the bricks on the pallets may be dried, either by passing the cars very slowly through that house, or by removing the pallets from the transporting mechanism and resting the same on shelves or brackets during the drying period; I have next shown the transporting system as passing through 90 into the kiln-shed, so as to deliver the pallets in close proximity to the kilns; and I have finally shown the transporting mechanism as returning to the starting point. As far as the present invention is concerned the origin of the bricks is wholly immaterial, as 95 is also the mode of their disposition upon the pallets.

Traversing the kiln shed C I have shown the tracks E—E of a traveling crane, which in the present embodiment I have also shown as extending through the drying house C so that the same crane can be employed for 105 moving the pallets from the transporter to the drying bracket, or from the transporter to the kilns, or from the drying brackets to

the kilns. The crane preferably comprises a rectangular frame F supported by suitable wheels G—G upon the tracks E, and itself forming a transverse track for the wheels 5 H—H of the car I. Mounted upon the car I is the rotary turn table J carrying the hoisting drums K and L. The frame F is driven along the rail C by the motor M; the car I is driven along the frame F by the motor N; the turn-table J is rotated by the motor O; the drum K is operated by the motor P; and the drum L is operated by the motor R; these motors are governed by suitable controllers located in the operator's 10 cage Q which depends from the platform I as usual in traveling cranes. Depending from the drum K are the falls S, and depending from the drum L are the falls T. It will be understood that the foregoing crane 15 construction is illustrative merely and that numerous other conveying expedients can be employed within the scope of my invention.

The carrying device herein shown consists 20 of a large, flat, rectangular tray or pallet 25 preferably provided with spaced transverse strips defining brick receiving channels, the length and width of the pallet being sufficient to hold the desired number of bricks. 30 Preferably, in case the pallet is to be used in kiln-building, its length is equal to (or at least commensurable with) the width of the body of the kiln which is to be built therefrom, in the present embodiment shown at 35 thirty feet; while its width depends upon the width of the tram-way or conveyer or upon the width of the passageways through which the same must pass. In the present embodiment I have shown a pallet having a 40 width of eight feet, thereby holding ten bricks of ordinary size arranged end to end.

Each of the brick carriers or pallets herein shown comprises a pair of longitudinal wood stringers 1, 1, upon which are secured transverse planks 2, 2, surmounted by a thin steel plate 3 which covers the whole device and upon the top of which are screwed or bolted the transverse strips 4—4. These strips are spaced apart a distance necessary to receive 45 whatever number of bricks are to be introduced between them. In the present case I have shown the bricks as delivered in pairs, that being one common mode of delivering bricks from brick machines and building 50 the same into kilns at the present day, although other arrangement can be employed within the scope of my invention. A thirty foot pallet so arranged presents seventy grooves, so that its load is fourteen hundred 55 bricks, and the total weight of bricks and pallet is about three tons. Of course the pallet could be made considerably smaller or somewhat larger if desired.

When the pallet is arranged for the purpose of building a kiln, as illustrated herein,

the width of the strips is such as to afford the desired lateral spacing of the bricks in that kiln. In case the carrying device is to be used for the purpose of building other structures than kilns or of loading, or transferring, or piling burned bricks, its construction and size will naturally be changed according to the work in view and the amount of movement necessary.

In order to discharge the bricks from the carrying device the same is first conveyed to the point where the bricks are to be set down, then inclined to such an angle that the bricks will slide easily and smoothly therefrom and finally drawn slowly rearwardly, while maintaining its lower edge closely adjacent to the supporting surface on which the bricks are to be laid, whereupon the bricks will slide gently and uniformly from their channels and be set down in exactly the predetermined relation. For the purpose of building a kiln this method offers peculiar and unusual advantages: for not only are the bricks spaced apart laterally by the width of the strips 4, 4, but the mode of their ejection from the pallet causes them to assume relatively angular positions at the moment of leaving the same, as shown in Fig. 4 which wedges the adjacent bricks apart, and produces a uniform longitudinal separation. The result is that by laying adjacent courses at right angles to each other (which is easily effected by rotating the turn-table J) a perfectly uniform regular porous pile can be constructed. In building a kiln directly from the pallets it is desirable that only one layer of bricks be placed upon the pallet at a time, since plural layers interfere with each other and do not produce equal spacing, but it is entirely feasible to transport and discharge a plurality of layers simultaneously, especially if the inclination of discharge be decreased and pushing means employed to assist the same.

For handling pallets I prefer the construction shown in Figs. 2, 4 and 6 consisting of a carrier adapted to hang substantially horizontal when suspended from the crane, and capable of being tilted in such a way as to afford the pallet the necessary inclination. This carrier comprises a rigid metal frame 10, preferably of trussed construction, adapted to overlie the pallet and having at one side a depending portion to which are secured a plurality of stiff metal arms 11, 11, adapted to underlie the pallets in supporting relation. These arms extend parallel to each other parallel to the strips 4 on the pallets and are provided with projections 12 adapted to engage suitable abutments on the pallets, such as the side of one of the stringers 1, and prevent the pallet from slipping. The frame is provided at the point nearest the free ends of the arms 11 with anchorage 13 for a cable 14 to which

are attached the falls S; and the rearward part of the frame is provided with another anchorage 15 for a cable 16 to which are attached the falls T. Each anchorage is 5 preferably made double and the corresponding cable attached in the familiar V fashion so as to diminish side sway or teetering of the carrier; and the forward anchorage 13 is located at such a point as always to lie 10 forward of the center of gravity of the carrier and pallet even when the entire load is confined to the forward edge of that pallet. The other anchorage 15 is located upon the opposite side of the center of gravity so that 15 by suitable relative movement of the falls the carrier and pallet can be given any desired inclination within wide limits.

In order to permit the insertion of the carrier-arms beneath the pallets, the latter 20 are supported in such wise upon the transporting device as to afford the necessary space therebeneath. Thus, in the case of the cable conveyer shown in Figs. 2 and 3, the ropes or cables 20 which ordinarily pass 25 over the tops of suitable rollers 21 carried on suitable standards 22, may be abruptly depressed and caused to pass beneath the pulleys 24, 24, additional idle rollers 25, 25, being provided for the reception of the pallets and affording sufficient space beneath 30 those pallets for the insertion of the arms 11 as clearly shown in Fig. 3. In case a car is employed as shown in Fig. 8, the top or floor 30 of the car is preferably provided 35 with spaced blocks 31, 31 so spaced and of such height that the arms can be inserted therebetween. The width of the carrier depends upon the length of the pallet, and the spacing of the fingers 11 upon the strength 40 and stiffness of that pallet. I prefer to locate the same between three and four feet apart.

The arrangement and construction of the kilns as shown at C is entirely independent 45 of the present invention, although I prefer to construct and arrange them as illustrated, described and claimed in my copending application filed March 18, 1918, Serial No. 223,026. The transporting device C is preferably 50 arranged to make a right-angular turn at some point within the travel of the crane, such as shown at 35 in Fig. 1, so that the orientation of the pallet will depend upon whether it is picked up at one side or 55 the other side of that turn. Also the dry house, when used, preferably has its shelves or brackets arranged at right angles to each other as shown at W, so as to allow the pallets to be set thereon in either position. 60 This expedient diminishes the necessity of swinging the pallets in mid-air, although this is entirely possible if desired and in fact has to be done in case the pallet is not entirely emptied when one course is completed; however I prefer to use the turn- 65

table chiefly for the purpose of changing the relative position of the falls since the rotation of the entire pallet, particularly when loaded, tends to set up violent torsional vibrations.

In the use of the apparatus and the performance of the method here disclosed, the pallet loaded in any suitable manner having been brought beneath the crane, the carrier is inserted beneath the pallet and the latter raised, the falls being operated simultaneously so as to maintain the arms and pallet substantially horizontal. Upon arrival at the place of discharge, the falls S 70 are lowered, and the falls T are raised so as 75 to incline the pallet and to present it closely to the receiving surface as shown in Fig. 5, after which the appropriate motor M or N is set in operation so as to draw the pallet 80 horizontally across the receiving surface in 85 a direction opposite to that in which the pallet is inclined. In starting a new layer 90 of bricks in an exposed position, a suitable guide is preferably employed, such as a plank 36, held in place by workmen until 95 the first brick of the series has been deposited. If it is desired to build only a narrow pile, for example such a pile as exists between the adjacent arches at the bottom 100 of the kiln, it is possible to stop the discharge of bricks at any moment merely by elevating the falls S and releasing the falls T, as shown in Fig. 4; in such a case the transverse courses are constructed, either by loading the pallet originally only as to certain grooves (which may be conveniently marked with paint or the like) or by preventing discharge in certain of the grooves by suitable gates or obstructions. For this reason the device is useful for a great many 105 purposes other than building kilns; and even in kiln building, it is customary to inclose the interior of the kiln with hand-laid walls after the middle part has been laid as 110 illustrated herein; and for the delivery of the necessary bricks to the workmen, I preferably employ the same discharging arrangement, piling the bricks upon the ground along the side of the kiln in any desired order and arrangement by means of 115 my improved apparatus.

The rapidity of laying the kilns depends upon the nature of the clay and its condition when delivered thereto; some clays can be built into the kiln immediately upon 120 pressing and without any drying whatever, provided not too many courses be laid in any one day; in such a case three or four courses may be laid over a large number of kilns, and additional courses may be deposited thereon on succeeding days. Other clays are necessarily dried before handling after which they may be built into kilns as rapidly as desired. When a drying house is used, its construction is largely immate- 125 130

rial; for example the bricks may be dried on small pallets or singly and placed upon the large pallets herein described after the drying is completed; or the large pallets can 5 be loaded previously, and the bricks dried thereon, either by passing said pallets slowly in a continuous manner through a heated chamber, or by setting said pallets off on to brackets or shelves and leaving them 10 for the requisite time. For the purposes of this invention the method of loading and conveying the pallets is not important since the loading may be done either by hand or machine, and the conveying by push-car, 15 cable-car, cable-carriers, or animal-drawn vehicles.

It will be understood that I do not limit myself to the force of gravity as the sole means for discharging the bricks from the 20 carrier. Within the scope of my invention I may employ a pushing means to assist the same as already suggested. For example, I have shown such a device in Fig. 5 wherein 40 represents a suitable pusher bar carrying one or more racks 21 perpendicular thereto and meshing with a pinion or pinions 42 carried by the frame 10 and adapted to be operated by suitable means such for example as the crank 43. Also it will be 25 understood that the invention is not necessarily limited to a device presenting a large number of grooves or chutes, or to any specific type of pallet, carrier, crane, or other device except as distinctly specified in the 30 claims.

It will also be understood that my improved brick handling mechanism is not restricted to the building of kilns or other structures since the bricks can, if desired, 40 be deposited upon some other receiving surface, such as an intermediate pallet, wagon, or car and thence transferred to any place desired, in which case the brick-carrier instead of being of the size of a kiln will be 45 made considerably smaller. It is also obvious that the transporting devices can be attached more directly to the brick receiving device than I have specifically illustrated and I do not restrict myself to the employment 50 of carrying device or pallet separate from the supporting and conveying devices except as and where specifically claimed. It will also be understood that by illustrating the bricks laid upon the carrying device in a single course or layer only, I am not restricted against the simultaneous handling and discharging of a plurality of layers except as to the few claims wherein this limitation is specifically recited.

60 Having thus described my invention, what I claim is:

1. In apparatus of the type described, in combination, a supporting device adapted to receive a plurality of laterally spaced rows 65 of longitudinally abutting brick, means for

transporting said supporting device from point to point and for presenting it above a receiving surface, means for inclining said supporting device in the direction of said rows of brick while so presented above such 70 surface, means for moving said supporting device bodily along such surface while so inclined, and means carried by the supporting device to guide each row of bricks during the discharging operation. 75

2. In apparatus of the type described, in combination, a supporting device having a plurality of spaced grooves or chutes thereon adapted for the reception of brick in longitudinal rows, means for transporting 80 said device to a point above a receiving surface and for inclining it in the direction of such rows, and means for moving said device bodily along such surface in a direction opposite to its direction of inclination. 85

3. In apparatus of the type described, in combination, a supporting device having a plurality of spaced grooves or chutes thereon adapted for the reception of brick in longitudinal rows, means for transporting 90 said device to a point above a receiving surface, means for orienting said device to point said rows in any desired direction, means for inclining said device in the direction of orientation, and means for moving 95 said device bodily in a direction opposite to its direction of orientation while maintaining its inclination substantially constant.

4. In apparatus of the type described, in 100 combination, a pallet having spaced grooves or chutes thereon adapted for the reception of brick in longitudinal rows, means for transporting said pallet from point to point, means for removing said pallet bodily from 105 said transporting means and for presenting the same above a receiving surface, means for inclining said pallet while so presented, and means for moving said pallet parallel to the receiving surface during the dis- 110 charge of the bricks thereon.

5. The combination with pallets having spaced grooves thereon adapted for the reception of brick in longitudinal rows, of means for transporting said pallets in a 115 horizontal plane, a traveling crane, a pallet carrier supported by said crane, means for orienting said carrier, said transporting device making a right angle turn within the limit of movement of said crane whereby 120 said pallets may be presented in either terrestrial direction, and means carried by said crane for inclining a pallet in the direction of its orientation.

6. The combination with a brick carrying 125 device having a receiving part adapted for the reception of parallel rows of longitudinally abutting bricks, said device having a forwardly facing discharging side perpendicular to said rows, of means for trans- 130

porting said device with its rows substantially horizontal, and for presenting the same with its discharging side above and close to a horizontal receiving surface, 5 means for moving said device horizontally rearwardly over said surface in a direction parallel to said rows while preventing the bricks from accompanying such horizontal movement, whereby the latter will be deposited 10 in orderly rows, and means for imparting to the bricks an inclined position at the instant of their discharge.

7. The combination with a brick carrying device having spaced parallel channels 15 adapted for the reception of rows of bricks arranged end to end, said device having a discharging side perpendicular to said rows, of means for moving said device horizontally in a direction parallel to said channels, means for presenting said device above 20 a horizontal receiving surface with said discharging side close to and parallel with the same, means for moving said device bodily across said receiving surface in a horizontal 25 plane and in a direction opposite to the direction in which said discharging side faces, and simultaneously preventing the horizontal movement of said bricks whereby the latter are deposited upon said receiving surface 30 in orderly rows, and means for imparting to the bricks an inclined position at the instant of their discharge.

8. The combination with a brick carrying device having spaced parallel channels 35 adapted for the reception of rows of bricks arranged end to end, said device having a discharging side perpendicular to said rows, of means for moving said device horizontally in a direction parallel to said channels, 40 means for presenting said device above a horizontal receiving platform with said discharging side close to and parallel with the same, means for moving said device bodily across said receiving surface in a horizontal 45 plane and in a direction opposite to the direction in which said discharging side faces, and simultaneously preventing the horizon-

tal movement of said bricks whereby the latter are deposited in orderly rows, and means for shifting by 90° the relative position of said device and platform between the deposition of successive courses whereby the rows of such courses will be perpendicular to each other. 50

9. In mechanism of the character described, the combination, with a brick carrying device adapted for the reception of bricks in orderly rows, of means for moving said device horizontally while preventing the bricks from accompanying such movement, whereby said bricks will be deposited upon a receiving surface, means for guiding said bricks during such deposition, and means for imparting to each brick at the instant of its deposition an inclined position relatively to the brick ahead. 60

10. In mechanism of the character described, the combination, with a brick carrying device adapted to receive rows of longitudinally abutting bricks, of means for holding said bricks against horizontal movement while simultaneously withdrawing said carrying device from beneath said bricks, whereby the latter may be deposited in orderly relation upon a receiving surface, and means for imparting to each brick at the instant of its deposition an inclined position relatively to the brick ahead. 70

11. The method of setting bricks upon a receiving surface which consists of, first, loading the bricks in the desired relation upon a carrying device, second, moving said device to a position above and close to the receiving surface, and inclined in the direction of discharge, and, finally, drawing said device past the receiving surface in a direction opposite to its inclination, while preventing said bricks from accompanying said device whereby they will be deposited upon said surface. 80 85

In testimony whereof, I hereunto affix my signature.

WILLIAM W. DICKINSON, Jr.
